PORTABLE DOLLHOUSE

Marilyn Griffith, Los Angeles, Calif.

Application May 12, 1951, Serial No. 15,150

Term of patent 7 years

(Cl. D34—11)

To all whom it may concern:

Be it known that I, Marilyn Griffith, a citizen of the United States of America and a resident of Los Angeles, county of Los Angeles, State of California, have invented a new, original, and ornamental Design for a Portable Dollhouse, of which the following is a specification, reference being had to the accompanying drawing, forming a part thereof.

In the drawing:

I claim:

The ornamental design for a portable dollhouse, substantially as shown.

MARILYN GRIFFITH.
